DESIGN FOR A GAME BOARD

Sigvald V. Lervaag, Little Falls, Minn.

Application April 27, 1945, Serial No. 119,274

Term of patent 7 years

(Cl. D34—5)

To all whom it may concern:

Be it known that I, Sigvald V. Lervaag, a citizen of the United States, residing at Little Falls, in the county of Morrison and State of Minnesota, have invented a new, original, and ornamental Design for a Game Board, of which the following is a specification, reference being had to the accompanying drawing, forming a part thereof.

I claim:

The ornamental design for a game board, as shown.

SIGVALD V. LERVAAG.
